(57) **CLAIM**

We claim the ornamental design for an inertial shooting counter, as shown and described.

DESCRIPTION

FIG. 1 is a bottom view of the inertial shooting counter in an assembly in accordance with our invention; FIG. 2 is a front view of the inertial shooting counter; FIG. 3 is a right side view of the inertial shooting counter; FIG. 4 is a rear view of the inertial shooting counter; FIG. 5 is a left side view of the inertial shooting counter; FIG. 6 is a top view of the inertial shooting counter; and, FIG. 7 is a perspective view of the inertial shooting counter. The broken line showing of the inertial shooting counter in FIG. 7 is for the purpose of illustrating the environmental structure and forms no part of the claimed design.
